United States Patent

Des. 241,402
Patented Sept. 14, 1976

241,402

COFFEE BASKET

David Painter, Glenview, Ill., assignor to Dart
Industries Inc., Los Angeles, Calif.

Filed Apr. 28, 1975, Ser. No. 572,548

Term of patent 14 years

Int. Cl. D7—04

U.S. Cl. D7—68

FIG. 1

FIG. 2

FIG. 3.

FIG. 4.

FIG. 1

FIG. 2

FIG. 1 is a side elevation view of a coffee basket embodying my ornamental design;

FIG. 2 is a top plan view thereof;

FIG. 3 is a front elevation view thereof;

FIG. 4 is a bottom plan view thereof;

FIG. 5 is a back elevation view thereof; and

FIG. 6 is a cross-section view taken along the line 6—6 of FIG. 2.

I claim:

The ornamental design for a coffee basket, substantially as shown and described.
